[57] CLAIM

The ornamental design for a charger base housing, as shown and described.

DESCRIPTION

FIG. 1 is a top, left, front, perspective view of charger base housing;

FIG. 2 is a right side elevation view thereof;

FIG. 3 is a bottom plan view thereof;

FIG. 4 is a rear elevation view thereof; and,

FIGS. 5–10 are top, left, front, perspective views of alternate embodiments of a charging base housing.

The broken line showing throughout the disclosure is included for the purpose of illustrating environmental structure only and forms no part of the claimed design.
